(57) **CLAIM**

The ornamental design for a microdrop dispensing adapter for eye dropper bottle, as shown and described.

DESCRIPTION

FIG. 1 is a perspective view of a microdrop dispensing adapter for eye dropper bottle showing my new design.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof.

FIG. 8 is an exploded view thereof showing the components of the microdrop dispensing adapter for eye dropper bottle.

FIG. 9 is a perspective view of a first component of the microdrop dispensing adapter for eye dropper bottle.

FIG. 10 is a front view thereof.

FIG. 11 is a back view thereof.

FIG. 12 is a right side view thereof.

FIG. 13 is a left side view thereof.

FIG. 14 is a top view thereof.

FIG. 15 is a bottom view thereof.

FIG. 16 is a perspective view of a second component of the microdrop dispensing adapter for eye dropper bottle.

FIG. 17 is a front view thereof.

FIG. 18 is a back view thereof.

FIG. 19 is a right side view thereof.

FIG. 20 is a left side view thereof.

FIG. 21 is a top view thereof.

FIG. 22 is a bottom view thereof.

FIG. 23 is a perspective view of a third component of the microdrop dispensing adapter for eye dropper bottle.

FIG. 24 is a front view thereof.

FIG. 25 is a back view thereof.

FIG. 26 is a right side view thereof.

FIG. 27 is a left side view thereof.

FIG. 28 is a top view thereof.

FIG. 29 is a bottom view thereof; and,

(Continued)

FIG. 30 shows a sectional view of the microdrop dispensing adapter for eye dropper bottle. The broken lines in the drawings depict features that form no part of the claimed design.
